[57] ABSTRACT

A coin counter or verifier has at least one straight edge along which are a series of regularly spaced ribs extending outwardly from the base of the counter. The ribs are sized according to the denomination of coin to be counted, operation of the counter entailing the insertion of the edge with the ribs into a trough of coins along one side thereof. The ribs force coins at regular intervals out of alignment in the trough to facilitate counting thereof.

BY PATENT AGENT

COIN COUNTER OR VERIFIER

The present invention relates generally to coin counting and wrapping devices, and particularly to a compact simple device designed to provide fast accurate counting of roll-size units of coins, or of partial rolls.

Prior to the development of nickel alloy coins it was generally true that coins could not be counted by stack length due to significant variations in individual coin thickness. This was especially true of coins with a high silver content as they had low abrasive resistance. The recent change to nickel alloy coins and improved minting standards has provided coinage of considerably improved dimensional stability and of increased durability. As a result it is possible to rely to a greater extent on coin thickness to provide an efficient method of counting coins.

The main feature of the invention, therefore is the provision of a means whereby coins arranged in a horizontal stack of normal roll-size quantities or less can be monetarily arranged in small groups suitable for rapid visual counting and verification. It is to be understood that coins are held in a trough-like container which supports them readily in a stacked configuration. Such a trough-like container may be found in my Canadian Pat. No. 769,469, issued Oct. 17, 1967, for a compact coin sorter and counter.

The coin counter of this invention includes a base having at least one side operative for coin counting. Along that side is a lip having a plurality of regularly spaced upstanding ribs, the spacing of the ribs being determined by the dimension of the particular denomination of coins to be counted.

The coin counter will accommodate variations in coin thickness due to wear or misuse. The coin count is accomplished by counting the coins which are displaced from a stack of coins by the ribs when the lip is forced into the trough adjacent the edges of the coins. Identification markings on the base give a monetary value to the total number of coins counted.

The invention will now be described in more detail and with reference to the drawings wherein:

FIG. 1 is a perspective view of the coin counter of this invention, and

FIG. 2 is a perspective view of the coin counter of this invention shown in use.

A preferred embodiment of the coin counter of this invention is illustrated in the drawings. In this embodiment the counter 10 is moulded from any suitable plastics material and has an essentially square perimeter.

Along each side is a plurality of regularly spaced ribs 11 projecting outwardly from the base 10 and upwardly from lips 12. These ribs therefore define spaces 13 therebetween. The lip 12 is of the same thickness and parallel to and offset from said base to facilitate insertion into a stack of coins. The lip and the base are jointed together by slanting portion 14. The depth of each lip, as well as the thickness of each rib and the interval or space between ribs is directly related to the dimensions of the denomination of coins to be counted. More uniform shrinkage during the moulding process is achieved if the base 10, lip 12 and slanting portion 14 are of the same thickness.

If, for example, coins having a base unit of five are to be counted, ribs 11 will be less thick than the base coin. Spaces 13 will, in turn, be wider than four such coins

placed face to face but narrower than five such coins. Coins of various denominations may easily be counted, each denomination being allocated to one side of the counter. While the preferred embodiment as shown has four sides, the number of sides provided is actually related to the number of denominations to be counted.

For convenience, handle 15 is integrally moulded into the base 10 of the counter. In addition, each side may be labelled with the denomination to be counted 10 thereon, as at 16, and the actual value may also be marked adjacent the appropriate rib, as at 17.

When counting coins, the counter is used in a manner as illustrated in FIG. 2 in association with, for example, a coin sorter according to my aforementioned Canadian patent. The coins 19 are stacked in a trough 18 of the coin sorter and the appropriate lip 12 of the counter is inserted into the stack along one side of the trough. As the lip goes deeper into the trough, ribs 11 will force every fifth coin 20, for example, partially out 20 of the stack. The four intervening coins will be within the confines of space 13. It is then possible to visually check the pattern to ascertain if the count is accurate, if excess coins are present or if additional coins are required. Removing the ribs from the stack of coins allows 25 the coins to slide downwards back into the trough ready for adjustment, roll wrapping or return to cash drawers.

In the event that the count is irregular, due to bent or worn coins, the irregularity will be immediately apparent as one rib will be supporting two coins. Since the spaces are too narrow to provide entrance of an extra coin, it is impossible to have excess coins within a space between ribs. On the other hand, if too few coins are present in the pattern, this fact can be quickly and visually determined when the coins are missing from a space and even more so when a coin is missing from a rib.

The coin counter of this invention provides a simple and inexpensive means for determining the number of 40 coins in a stack thereof. It is easily manufactured using modern moulding techniques and it is sufficiently compact in size to be carried in pocket or purse.

The embodiments of the invention in which an exclusive property or privilege is claimed are defined as follows:

1. A coin counter comprising a base having at least one straight side and a lip offset from said base and forming an obtuse angle with an outwardly slanting portion of said base, said lip rigidly supporting a plurality of regularly spaced ribs, said ribs extending upwardly from said lip and outwardly from said base, the spacing of said ribs being denominationaly related to the coins to be counted.

2. A coin counter comprising a base having at least one straight side and a lip for rigidly supporting a plurality of regularly spaced ribs extending upwardly from said lip and outwardly from said base wherein the spacing of said ribs is denominationaly related to the coins to be counted and each rib has a thickness less than 55 that of a coin to be counted.

3. A coin counter according to claim 2 wherein said base is square in configuration, the ribs along one side thereof being regularly spaced with intervals therebetween different from the intervals between the ribs of another side.
